(57) CLAIM

The ornamental design for a tent, as shown and described.

DESCRIPTION

FIG. 1 is a front, left side, perspective view of the tent showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a front, left side, perspective view, similar to that of FIG. 1, showing, however, the tent in a state of use where the left side and front flaps have been rolled open so as to permit entry into and exit out from the tent.

The broken lines are for the purpose of illustrating portions of the article that form no part of the claim.
